UNITED STATES PATENT OFFICE.

JOHN L. FLANNERY, JR., OF CHICAGO, ILLINOIS, ASSIGNOR TO THE BOYE NEEDLE COMPANY, OF CHICAGO, ILLINOIS, A CORPORATION OF ILLINOIS.

DESIGN FOR A LABEL.

53,120.

Specification for Design.

Patented Mar. 25, 1919.

Application filed December 21, 1917. Serial No. 208,325. Term of patent 7 years.

To all whom it may concern:

Be it known that I, JOHN L. FLANNERY, Jr., a citizen of the United States, residing at Chicago, county of Cook, and State of Illinois, have invented a new, original, and ornamental Design for a Label, of which the following is a specification, reference being had to the accompanying drawing, forming a part hereof.

The figure is a plan view of a label in accordance with the design.

I claim:

The ornamental design for a label as shown.

JOHN L. FLANNERY, JR.
